GRENADE THROWER

Cesar Bustamante, New York, N. Y., assignor to
Elie Gut, New York, N. Y.

Application November 13, 1942, Serial No. 465,426

9 Claims. (Cl. 124—6)

This invention relates to grenade throwers, and more particularly to a centrifugal gun for throwing grenades or projectiles of frangible material, containing inflammable or explosive material, and has for its object the provision of an improved grenade throwing apparatus. The device may also be used for throwing or "firing" solid projectiles of metal or metal projectiles containing explosives.

The present invention aims to provide a centrifugal mechanism which imparts velocity and momentum to the projectile without causing the projectile to rotate on an axis at right angles to the direction of its travel, thereby improving the accuracy of such guns in hitting the target.

An object of the invention also is to provide a centrifugal gun which is so constructed that it can be aimed with precision.

A further object of the invention is to provide a centrifugal gun which is of rugged construction and which can be manufactured at moderate cost.

The invention will be understood from a consideration of the following description taken in connection with the accompanying drawings which illustrate one embodiment of the invention. It is to be understood, however, that these drawings are merely illustrative of the invention and that the invention is not limited to the construction illustrated but that its scope is set forth in the appended claims:

In these drawings:

Fig. 1 is a view of the apparatus in side elevation looking from the left of Fig. 2;

Fig. 2 is a view in front elevation, or looking from the right of Fig. 1, with certain parts broken away;

Fig. 3 is a vertical section taken on line 3—3 of Fig. 2;

Fig. 4 is a sectional view to illustrate the details of the loading mechanism and is taken on plane 4—4 of Fig. 1;

Fig. 5 is a sectional detail of the magazine feeding mechanism and is taken on plane 5—5 of Fig. 1;

Figs. 6 and 7 are views of the centrifugal throwing mechanism in different positions, Fig. 6 representing the loading position and Fig. 7 the discharge position; and

Fig. 8 is a perspective view of a magazine.

Referring now to the accompanying drawings, the centrifugal gun comprises in general three similar rectangular frame members 1, 2 and 3 arranged in vertical parallel spaced relation to one another and resting on two transverse sup-

ports 4 shown as channel members. The supports 4 are provided with wheeled casters 5 which roll upon a base member 6. A pivot pin 7 is fixed to base member 6 and passes through an aperture in a cross plate 8 secured at its opposite ends to the lower edges of frame members 1 and 2. Pivot pin 7 has a head which engages the upper surface of plate 8 to retain the superstructure of the gun on its base. This pivot provides a means by which the gun may be trained on the target, as will be described later.

Frame members 1, 2 and 3 are tied together at their corners by long bolts 9 and suitable spacers 10 so as to form a rigid structure. Frame members 2 and 3 are provided, somewhat above their centers as viewed in Fig. 3, with channels in which the main shaft 11 is mounted for rotation. Shaft 11 at its left hand end, as viewed in Fig. 2, has secured to it a rotor 12, and also fixed to this shaft between frames 2 and 3 is a driving gear 13.

Gear 13 is driven by means of a pinion 14 which is fixed to a jack shaft 15 journaled between frame members 2 and 3 immediately below shaft 11. Jack shaft 15 and shaft 11 are continuously driven by means of a chain 16 which passes over suitable sprockets mounted respectively on shaft 15 and on a third shaft 17 which is journaled in all three frame members 1, 2 and 3 and extends to the left, as viewed in Fig. 2, behind frame 1. Shaft 17 is driven by another chain 18 from driving motor 19 (Fig. 1) which is located to the left of frame member 1 as viewed in Fig. 2. This motor will ordinarily be an internal combustion engine in order that the unit may be mobile, although any appropriate source of power may be used.

Briefly describing the operation of the grenade thrower or gun of the present invention, the projectiles 20 are fed successively into the apparatus from the left, as viewed in Figs. 2 and 4, in line with the axis of main shaft 11. They are received one at a time at the loading position 20L (Fig. 6) at the center of rotation of rotor 12 in a suitable holder mounted on a carrier which moves the projectile from this position to a position which is eccentric to the axis of the shaft 11 such as the position indicated by reference numeral 20R in Fig. 7, which shows the projectile undergoing release from the gun. At this point of release a predetermined velocity and momentum have been imparted to the projectile and the projectile commences its flight, the first part of which is substantially tangential to a circle whose center is the axis of shaft 11.

The carrier is a rotary device and moves in the direction of the arrows slowly relative to the angular movement of rotor 12, the rotor making a plurality of revolutions during the movement of the projectile from the position of Fig. 6 to that of Fig. 7.

In the embodiment illustrated a pair of spaced arms 21 comprise the carrier, these arms being fixed midway between their ends to a shaft 22 which is mounted for rotation in a bearing member 23 mounted on the rotor 12 approximately midway between the center of the rotor shaft 11 and release position 20R (Fig. 7). Rotor 12 comprises a plate of suitable thickness to support the bearing 23 for carrier shaft 22 and is provided with a widened portion 24 to serve as a counterbalance.

Rotor 12 also has diametrically opposite counterweight portion 24 a forked extension at the tips of which are two supporting posts 25 which serve to in part support a semicircular guard segment 26, the purpose of which will appear presently. This segment is also supported on rotor 12 by two additional posts 27. Guard segment 26 is held by these posts in fixed spaced parallel relation to the left hand surface of rotor 12, as viewed in Fig. 2.

Carrier arms 21 are mounted on a hub 28 which is pinned or keyed to shaft 22, as indicated in Fig. 2, and which serves to hold the arms spaced apart. These arms 21 are forked at one end to receive the projectile holder 29 which comprises a curved U-shaped plate having one leg of the U longer than the other and which is seated in the recesses which form the forks. Projectile holder plate 29 is supported by both of the arms 21 as shown in Fig. 2 and its length is substantially that of the cylindrical projectiles 20.

The outwardly open end of holder 29 is closed by means of a curved releasable cover 30 (Fig. 3) which is carried between two pivoted curved and somewhat L-shaped arms 31 which are pivoted at 32, one on the outside of each of carrier arms 21. In order to hold cover 30 in closed position during the movement of the projectile from the loading position 20L of Fig. 6 to the release position 20R of Fig. 7, a roller 33 is mounted on a pin 34 which extends between the free ends of arms 31. Roller 33 engages the inner surface of semi-circular guard segment 26 during this movement, carrier 21 rotating in the same direction as rotor 12, as shown by the arrows.

Somewhat before the carrier has moved the projectile to the release position 20R, roller 33 leaves the end of segment 26 and engages the inner surface of a pair of arcuate releasing bars 35, to be described, which control the instant of release of the projectile. As roller 33 passes the corners 36 (Fig. 7) release takes place, cover 30 and its supporting arms fly outwardly under the action of central or centrifugal force, and thereby releasing the projectile.

In order to cushion the outward movement of cover 30 and its supporting arms, a cross bar 37 is provided between arms 31 which is apertured to receive a pair of bolts 38. These bolts are threaded at their inner ends into a cross member 39 extending between arms 21, and cushioning springs 40 are provided just under the heads 38 of the bolts against which cross bar 37 engages. Carrier 21 is provided at the end opposite the projectile holder with counterbalance weights 41

which also act as spacers between the two arms comprising the carrier.

The arcuate release bars 35 are so arranged that they can be rocked in the vertical direction about the axis of rotor shaft 11, thereby causing the releasing point 36 to be advanced or retarded. It will be understood that when this releasing point is advanced, that is, moved to the left in Fig. 7, the release of the projectile will take place earlier, 10 which will result in elevating the trajectory of the projectile. On the other hand if releasing point 36 is retarded, that is, moved to the right in Fig. 7, the opposite result will take place and the flight of the projectile will be lowered.

15 In order to mount the releasing bars 35 for such adjustment, they are mounted near their opposite ends on two long bolts 42 which are supported at their opposite ends on two bell crank shaped members 43. Bolts 42 are secured to the tips of the 20 arms of these two members 43 and the centers of these members are pivoted for the rocking movement described above, one on rotor shaft 11 adjacent frame member 2 and the other on the end of a hollow sleeve 44 which projects to the right 25 of frame member 1 in axial alignment with shaft 11. The two releasing bars 35 are maintained in properly spaced relation to one another and the two bell crank shaped members 43 are mounted in properly spaced relation by the use of spacing 30 sleeves 45 threaded upon the long bolts 42, as will be understood from Fig. 2.

One of the releasing bars 45 is provided with a handle 46 by means of which the apparatus can be turned on its main supporting pivot 7 so as to train 35 the gun on the target. It will be understood also that by moving this handle in a vertical plane the releasing bars will be rocked so as to advance or retard the releasing point 36 and in this way elevate or depress the trajectory in accordance with 40 the range. Sights (not shown) may be suitably mounted to facilitate in the aiming of the gun.

It is stated above that rotor 12 makes a predetermined number of revolutions between the time carrier 21 receives the projectile at position 20L (Fig. 6) and the time it transfers the projectile to the release position 20R; also a substantially equal number of revolutions of rotor 12 occur while the carrier is returning to the loading position. This movement of carrier 21 with respect to rotor 12 is 45 produced by the following mechanism.

Arranged to rotate freely on rotor shaft 11 to the left of frame member 2 (Fig. 2) there is a gear 47 which is driven by a pinion 48 keyed to shaft 15. The gear ratio of gear 47 and pinion 48 is 55 slightly higher than the gear ratio between gear 13 and pinion 14 by which shaft 11 is driven so that gear 47 rotates slightly slower than gear 13 and shaft 11 but in the same direction. In other words, gear 47 rotates slowly with respect to shaft 60 11 and in the same direction.

This slow rotation of gear 47 in the same direction as shaft 11 is communicated to shaft 22 on which carrier 21 is fixed by means of gearing indicated generally by numeral 49 and in the embodiment illustrated the arrangement is such that carrier 21 makes one complete revolution for each 20 revolutions of rotor 12; that is to say, during the movement of the carrier in transferring a projectile from loading position 20L (Fig. 6) to discharge position 20R (Fig. 7) the rotor makes approximately 10 revolutions, although it may be somewhat more or less, depending upon the elevation at which the gun is aimed, that is to say, the 70 angular position of release point 36. Also during 75

the continued rotation of carrier 21 to return the empty projectile holder 29 from the position 20R to the original loading position 20L, approximately another 10 revolutions of rotor 12 take place.

However, in order to facilitate the entrance of the projectile at the loading position 20L it is desirable to have the holder 29 pause for an instant, for example, for one or two or three revolutions of rotor 12 at the loading position 20L, although it is unnecessary for the carrier 21 to stop rotating at the discharge position 20R. This is provided for by employing as gearing 49 an intermittent gearing mechanism such as is indicated in Figs. 6 and 7. Hence gearing 49 comprises the intermittent gears 50 and 51 which operate in a well understood manner. These two gears 50 and 51 are of the so-called mutilated type, but other forms of intermittent gearing can be employed.

The feeding mechanism by means of which the projectiles are fed to the gun and into the loading position 20L is illustrated in Figs. 1-5, inclusive, and the magazine in Fig. 8 which is here shown as being empty. This magazine indicated by numeral 52 comprises an elongated channel-shaped member, in this instance adapted to contain twelve projectiles. The magazine is provided with a series of cylindrical chambers 53 which are fixed between the flanges of the channel member and each of which is adapted to contain a single cylindrical projectile. The web portion of the channel-shaped magazine 52 is provided with circular openings 54 opposite the center of each of the projectile chambers 53. One of the flanges of the magazine is provided with a series of equally spaced angularly positioned slots 55 into which the peripheries of feed screws 56 enter in feeding the magazine through the gun (Figs. 5 and 1).

As will be understood from Fig. 1, the magazine is slid by hand into the upper end of a slideway formed by two parallel guides 57 until the feed worms engage slots 55. These feed screws are keyed to an operating shaft 58 which is mounted for rotation alongside of guides 57 and which is rotated by beveled gearing 59. One of the gears of beveled gearing 59 is pinned onto a short shaft 60 and on the other end of this shaft there is pinned one of the gears of an intermittent gearing 61. The driving gear of this gearing is fixed upon main feed shaft 62 which is continuously rotated by means of worm gearing 63 from shaft 17.

The feeding mechanism just described operates to advance the magazine 52 in a step-by-step movement (this movement being obtained by the intermittent gearing 61) so as to bring the cylindrical chambers 53 with projectiles 20 therein successively into axial alinement with the hollow sleeve 42 which is in turn in alinement with the axis of rotor shaft 11. As each projectile arrives at this point it is pushed axially out of its chamber 53 into the interior of sleeve 44 by means of a reciprocating plunger 64 which operates through the openings 54 in the web of the magazine. On each advance of plunger 64 a projectile 20 which has previously been placed in sleeve 44 is pushed forward to the right (Figs. 2 and 4) into position 20L within the projectile holder 29. The projectiles are stopped in the proper position by means of a suitable stop device which may, for example, be the rounded end of shaft 11 as shown in Fig. 4.

The plunger 64 is mounted on a carriage 65 which is arranged to slide on two parallel rods 66 which project to the left of the apparatus as shown in Fig. 2. It is actuated by means of con-

necting rod 67 pivoted to carriage 65 (Fig. 4) and also to a small rotating crank 68 which is pinned to the upper end of a short shaft 69. On the lower end of this shaft there is one of the gears of a third intermittent gearing indicated generally by numeral 70. The other gear of intermittent gearing 70 is pinned or keyed on feed shaft 62 (Fig. 1).

It will be understood that the arrangement of 10 this feeding mechanism is such that for each 20 revolutions of rotor shaft 11 the magazine 52 is advanced a distance equivalent to that between two adjacent cylindrical chambers 53, and plunger 64 is also operated once to cause a projectile to be advanced into the projectile holder 29.

By means of the present invention there has been provided a centrifugal gun capable of throwing grenades or solid or explosive bullets or projectiles which will not only throw such projectiles 20 at high velocity and for great distances with accuracy, but which is reliable in operation, has comparatively few parts and does not have excessive weight.

It will be understood that the apparatus can 25 be modified to throw spherical as well as cylindrical projectiles and that other feeding mechanism 30 may be employed instead of that illustrated and described for feeding the projectiles into loading position; also that the intermittent gearing mechanism, particularly the intermittent gearing 49 35 may take other forms if desired. It will also be understood that other changes may be made in the embodiment of the invention which has been described without departing from the spirit thereof, the scope of the invention being set forth in the appended claims.

I claim:

1. A centrifugal gun comprising a continuously 40 rotating rotor, means for feeding projectiles successively to the center of rotation of said rotor and in timed relation to the rotation thereof, mechanism operating in timed relation to the rotation of the rotor for transferring the successive projectiles to a position eccentric to the center of rotation of the rotor, said mechanism including means to grip the individual projectiles and hold them fixed therein during said transfer and means for releasing the projectiles.

2. A centrifugal gun comprising a continuously 45 rotating rotor, a projectile carrier rotatably and eccentrically mounted on the rotor, said carrier having a holder to receive a projectile including means to grip the same and prevent its rotation therein, means for rotating the carrier to transfer the projectile from the center of rotation of the rotor to a position eccentric thereto, and means for releasing the projectile.

3. A centrifugal gun comprising a continuously 50 rotating rotor, a projectile carrier rotatably and eccentrically mounted on the rotor, said carrier having a holder to receive a projectile including means to grip the same and prevent its rotation therein, intermittently operating mechanism for rotating the carrier to transfer the projectile 55 from the center of rotation of the rotor to a position eccentric thereto, and means for releasing the projectile, said intermittently operating mechanism causing the carrier to pause at said center of rotation to receive the projectile.

4. A centrifugal gun comprising a continuously 60 rotating rotor, means for feeding projectiles successively to the center of rotation of said rotor in timed relation to the rotation thereof, mechanism operating in timed relation to the rotation 65 of the rotor for transferring the successive pro-

jectiles to a position eccentric to the center of rotation of the rotor, said mechanism including a holder adapted to grip individual projectiles and hold them fixed therein during said transfer and openable to release a projectile therein, and adjustable means for effecting the opening of said holder at a predetermined angular position of the rotor.

5. A centrifugal gun comprising a continuously rotating rotor, means for feeding projectiles successively to the center of rotation of said rotor in timed relation to the rotation thereof, mechanism for transferring the successive projectiles to a position eccentric to the center of rotation of the rotor, said mechanism including a holder adapted to grip individual projectiles and hold them fixed during said transfer, and adjustable means for releasing the projectiles at a predetermined angular position of the rotor, the rotor making substantially half as many revolutions during said transfer as between the feeding of successive projectiles.

6. A centrifugal gun comprising a continuously rotating rotor, a carrier adapted to transfer a projectile from the center of rotation of the rotor to a discharge position eccentric thereto, said carrier having a projectile holder opening outwardly, a cover member for retaining a projectile in said holder, said cover member being movable under the action of centrifugal force to a position to release a projectile for discharge from said holder, means carried by the rotor for holding the cover closed while the projectile holder moves outwardly to a position adjacent its discharge position, stationary means engageable by the cover just prior to the projectile holder's reaching its discharge position, said stationary means holding the cover closed until the cover moves from engagement therewith, said stationary means being adjustable with respect to the rotor to facilitate the aiming of the gun by shifting the discharge position.

7. A centrifugal gun comprising a continuously rotating rotor, a projectile carrier rotatably and eccentrically mounted on the rotor and adapted to transfer a projectile from the center of rotation of the rotor to a discharge position eccentric thereto, said carrier having a projectile holder opening outwardly, a cover member for retaining a projectile in said holder, said cover member being movable under the action of centrifugal force to a position to release a projectile for discharge from said holder, an arcuate member mounted on the rotor in position to be engaged by said cover to hold the same closed while the projectile holder moves outwardly from the center of rotation of the rotor and approaches the discharge position, a stationary arcuate member engageable by the cover just prior to the pro-

jectile holder's reaching its discharge position, said stationary arcuate member holding the cover closed until the cover moves from engagement therewith, said stationary arcuate member being angularly adjustable with respect to the rotor to retard or advance the release of the projectile.

8. A centrifugal gun comprising a continuously rotating rotor, a projectile carrier rotatably and eccentrically mounted on the rotor and adapted to transfer a projectile from the center of rotation of the rotor to a path of rotation of predetermined diameter, said carrier having a projectile holder opening outwardly, a cover member for retaining a projectile in said holder, said cover member being movable under the action of centrifugal force to a position to release a projectile for discharge from said holder, means carried by the rotor for holding the cover closed until the projectile holder moves outwardly to a position adjacent its discharge position, a member having a stationary arcuate surface adjacent said path of rotation, said arcuate surface being engageable by the cover just prior to the projectile holder's reaching its discharge position, said member holding the cover closed until the cover moves from engagement with said arcuate surface, said stationary member being angularly adjustable with respect to the rotor to retard or advance the release of the projectile.

9. A centrifugal gun comprising a continuously rotating rotor, a projectile carrier rotatably and eccentrically mounted on the rotor and adapted to transfer a projectile from the center of rotation of the rotor to a path of rotation of predetermined diameter, said carrier having a projectile holder opening outwardly, a cover member for retaining a projectile in said holder, said cover member being movable under the action of centrifugal force to a position to release a projectile for discharge from said holder, an arcuate member fixed to the rotor and engageable by the cover to hold the same closed while the projectile holder moves outwardly from the center of rotation of the rotor to a position adjacent its discharge position, a member having a stationary arcuate surface adjacent said path of rotation engageable by the cover just prior to the projectile holder's reaching its discharge position, said member holding the cover closed until the cover moves from engagement therewith, the movement of the cover member along the arcuate member fixed to the rotor bringing the cover member into engagement with said stationary member, said stationary member being angularly adjustable with respect to the rotor to retard or advance the release of the projectile.

CESAR BUSTAMANTE.
